[57] **CLAIM**

The ornamental design for a supplying unit for supplying a developer for a copying machine, as shown.

DESCRIPTION

FIG. 1 is a front, top and right side perspective view of a supplying unit for supplying a developer for a copying machine, showing our new design;

FIG. 2 is a top plan view thereof;

FIG. 3 is a front elevational view thereof;

FIG. 4 is a right side elevational view thereof; the opposite side being a mirror image;

FIG. 5 is a bottom plan view thereof;

FIG. 6 is a rear elevational view thereof; and,

FIG. 7 is an enlarged cross-sectional view taken along the line 7 —7 in FIG. 3.
